(57) **CLAIM**

The ornamental design for a cable tester transmitter and receiver set, as shown and described.

DESCRIPTION

FIG. 1 is a perspective view of a transmitter of a cable tester transmitter and receiver set showing my new design, shown separately for ease of illustration;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is a perspective view of a receiver of the cable tester transmitter and receiver set, shown separately for ease of illustration;

FIG. 10 is another perspective view thereof;

FIG. 11 is a front elevational view thereof;

FIG. 12 is a rear elevational view thereof;

FIG. 13 is a left side elevational view thereof;

FIG. 14 is a right side elevational view thereof;

FIG. 15 is a top plan view thereof;

FIG. 16 is a bottom plan view thereof; and,

FIG. 17 is a perspective view of the cable tester transmitter and receiver set.

The broken lines in the drawings depict portions of the cable tester transmitter and receiver set that form no part of the claimed design.
